NECKTIE RACK

Roger E. Davis, Traverse City, Mich., assignor to The Setwell Company, Traverse City, Mich., a corporation of Illinois

Filed Dec. 27, 1963, Ser. No. 77,947

Term of patent 14 years

(Cl. D33—8)

FIG. 1

FIG. 2

FIG. 3

FIG. 4

FIG. 1 is a front elevational view of a necktie rack embodying my new design;

FIG. 2 is a plan view thereof;

FIG. 3 is a left end view thereof; and

FIG. 4 is a section taken along line 4—4 of FIG. 1.

The design is characterized by the combination, disclosed in the drawing, of a pair of circular end caps and a helix spring arrangement, said arrangement being partially recessed in an elongated base member, said base member having a substantially plano-convex configuration, all as shown.

I claim:

The ornamental design for a necktie rack, as shown and described.
